WALTER A. HEINRICH, OF ST. LOUIS, MISSOURI

SUPPORTING DEVICE FOR ELECTRICAL EQUIPMENTS

Application filed October 10, 1930. Serial No. 487,890.

This invention relates to improvements in supporting devices for electrical equipment, and more particularly to an improved hanger adapted as a universal support for outdoor electrical equipment to be suspended from or supported by standard cross arms.

Except for pin-mounted apparatus, most of the overhead electrical appliances have heretofore been suspended from, or supported by cross arms through the use of a hanger or clamp, the body portion of which is of substantially U shape and the legs of which extend laterally of or below the arm, to be connected by a strap or plate, bolted into adjacency with one face of the arm. This and other older types of cross arm hangers are practically of predetermined dimensions, since three faces thereof are permanently structurally related, and of fixed angularity.

Hence for practical purposes a separate hanger has heretofore been required in connection with each cross arm of a different size. The inconvenience resulting from this necessity is obvious to those skilled in the art.

The present invention therefore has as an object, the provision of a cross arm hanger of universal application for the support of outdoor electrical apparatus, to any of the standard sizes of cross arms.

A further object of the invention is the provision of a cross arm hanger, which is not only adjustable in size to permit its use in connection with any standard size cross arm or like supporting member, but which has a wide range of adaptability for connection with any of a great variety of electrical devices, each of which heretofore may have been provided with its own peculiar style of mounting for association with a cross arm or like support.

Further objects and advantages of the invention will appear from the following detailed description, considered in connection with the accompanying drawing of preferred embodiments of the invention. In the drawing:

Fig. 1 is a side view of a preferred form of hanger as applied to a cross arm, which for convenience is shown in section; Fig. 2 is a front elevation of the clamp appearing in

Fig. 1, and Fig. 3 is a view similar to Fig. 1 and showing a slightly modified form of the invention.

Referring now by reference numerals to the drawing, the numeral 4 designates, in section, a cross arm of standard type with which is shown a two part hanger or supporting clamp, one half or part of which consists of a face 5, by preference slightly curved so as to conform to the usual cambered top surface of the cross arm, and a face 6, disposed at substantially a right angle with respect to the face 5. My preference is to extend each of the face portions 5 and 6 at one end thereof, to form an angularly disposed terminal clamping lug 7, companion mating terminal lugs being provided on the complementary portion of the clamp constituted by face portions 8 and 9, disposed in like manner at substantially a right angle 70 to each other.

Each half of the hanger may be formed of flat strip material, preferably galvanized or otherwise rust proofed. The mated terminal lug portions 7 are by preference provided with registered bolt openings adapted to accommodate the bolts 10, by which the two halves of the clamp are secured together about the cross arm.

The arrangement of parts is preferably such that the bolts 10 and clamping lugs are disposed at diagonally opposite corners of the substantially rectangular area enclosed by the hanger; each half of the clamp forming two sides of the rectangle defined by the clamp as a whole.

As a means for structurally associating, by preference in detachable relation, the electrical apparatus to be carried by the hanger, there is provided an extension formed in the present example by a pair of parallel arms 11 extended in a direction diagonally from one corner of the substantially rectangular area embraced by the hanger. The length 95 of the arms 11 will, of course, depend upon particular requirements of space insulation, etc., and may be determined by the nature and desired angular mounting of the particular apparatus to be connected thereto.

As a convenient means of bolting or otherwise securing the associated apparatus to the arms 11, there is provided a pair of bolt openings 12, aligned with each other transversely of the arms 11.

The arms of the extension are, by preference, joined to each other at the outer extremity of the extension by an end member 13 through which there is also provided a bolt opening 14, shown as occupied by an attachment bolt 15. Each of the bolt openings is, by preference, of rectangular shape, and of a size to receive the usual squared shank portion of a carriage bolt, so that a bolt of this type may be inserted in either direction and be positioned against rotation while threading up the nut thereon.

The device of Figs. 1 and 2 is particularly adapted for use in hanging or supporting a fuse switch assembly of a type described in detail in my copending application of Serial No. 487,889, filed Oct. 10, 1930. Obviously, the hanger clamp forming the subject matter of the present disclosure may be employed in connection with a variety of other apparatus.

In Fig. 3 there appears a side view of a modified form of the device as secured to a cross arm, the arm being shown in section as in Fig. 1. In the modified form, the face 9 by preference engages the top surface of the arm, the terminal lugs 7 being disposed similarly to the showing of Fig. 1, at or near the outside corner of the rectangle defined by the clamp, while the diagonally opposite lug 16 formed on face 8, is bent upon itself to form an end member 17, provided with a bolt opening 18, and further forming a leg portion 19 parallel to the lug 16. The portion 19 terminates in a flat, angular lip 20 adapted, in use, to lie flatly against the face 8, and may, if desired, be welded to the face. The members 16 and 19 are provided with registering bolt openings, as is apparent from the drawing, for the reception of a bolt 22 which, if desired may be provided with a pair of nuts 23.

In certain installations it may be desirable to provide an anchorage to resist movement of the clamp along the cross arm. To this end, one of the faces of the hanger, for example the top or curved face, may be provided with an aperture, through which a wood screw 24 may be driven into the arm. This expedient may obviously be employed in connection with either of the illustrated types of clamp.

The manner of use and application of the described hanger is thought to be fully apparent from the drawing, and from the preceding description of parts. To apply the hanger, it is merely necessary to remove the bolts such as 10 of Fig. 1, and 10 and 22 of Fig. 3. Upon application of the two parts

of the hanger about the arm, the bolts are again inserted and the nuts threaded up, as far as the size of the arm will permit. It will appear obvious that as the hanger is employed with relatively larger sizes of cross arms, the spacing of the terminal lugs will be correspondingly increased, but that nevertheless the clamp will, as a whole, substantially embrace, and engage the four faces of the cross arm. The use of attachment bolts such as 15 and 22 will permit the ready application of the associated apparatus to the hanger, so that in practice it is necessary to provide a temporary support for the electrical unit for only a time sufficient to make a single bolted connection thereof with the hanger.

As is known in the art, the cross arms of standard sizes, as usually furnished to the trade for overhead electrical line work, are of substantially uniform sectional proportions, so that through the range of usual sizes the sectional conformity appears substantially the same, although greater in sectional area in the larger sizes. Thus, the present provision of a two part clamp having angular faces in which the parts of the clamp are connected at diagonally opposite corners, results in a construction having practically universal adaptability for its intended purpose. The arrangement has been found in practice materially to reduce the necessary stock of cross arm parts required, not only by the manufacturer and jobber, but also by large users of equipment of this sort. This reduction in the number of different stock items is reflected in economies to the manufacturer and user, in fulfillment of the several objects heretofore set forth.

While I have illustrated and described in great detail but two different embodiments of the invention and have described their adaptation to the support of outdoor electrical equipment, it will appear obvious that a wide variety of other uses exist for a clamp of this type, and that a number of changes may be made in the arrangement, construction and combinations of parts constituting the device, without departing from the spirit and full intended scope of the invention, as defined by the following claims.

I claim as my invention:

1. A clamping device arranged for mounting electrical apparatus to a support therefor, said device including a pair of separable support-engaging members, each member having legs angularly disposed relative to each other, the legs of one of said members being bent outwardly near adjacent ends to provide a polygonal bracket for electrical apparatus to be supported, and means disposed near the outer ends of said legs for detachably securing the members together about the support.

2. A substantially rectangular clamp for

securement of electrical apparatus to a cross arm, said clamp including a pair of clamping members, each of angulate construction formed of flat, metal strip material and adapted to engage a pair of adjacent surfaces of the arm, one of said clamping members being bent outwardly to form spaced, yieldably related arms, a holding element associated with said arms, and means for detachably clamping said members together at diagonally opposite locations.

3. A hanger clamp for attachment to a cross arm, the clamp including a pair of separable clamping members, each of said members having a pair of face portions disposed at substantially a right angle to each other, each face portion being extended outwardly of the clamp to form a clamping lug disposed near one corner of the clamp and associated cross arm, and the clamping members being related for mutual clamped securement, through pairs of said lugs, with the paired lugs disposed substantially at diagonally opposite locations, one of said members having a reversely bent portion, projected away from its face portions, and adapted for connection to apparatus to be supported from the cross-arm.

4. A universal cross arm hanger including a pair of substantially V shaped clamping members, means for securing said members together about a cross arm, one of said members being bent away from its arm-engaging portion to form a loop portion, and holding means engaging said loop portion.

5. A cross arm hanger including a pair of angulate strap metal members arranged for securement to each other in opposed relation about a cross arm, one of said members terminating in an outwardly projecting polygonal loop to form an extension piece, adapted for attachment to apparatus to be supported by the cross arm and a bolt extending through said looped portion for securing said members together.

6. A cross arm hanger including two separable clamping portions, each of said portions having a pair of faces, each face conforming substantially to one face of the cross arm to be engaged thereby, the faces of each clamping member being disposed at substantially a right angle to each other, the clamping members being adapted for securement together in opposed relation to form a substantially rectangular enclosure; terminal projections associated with the clamping members and disposed at diagonally opposite corners of the hanger, and an extension disposed diagonally of the clamp for engagement with apparatus to be supported thereby, said extension including a pair of parallel arms provided with a bolt opening, and a bolt therethrough for engagement with the apparatus to be supported.

WALTER A. HEINRICH.
